PLAYGROUND CLIMBER

Robert S. Wormser, Hillsdale, Mich., assignor to Game Time, Inc., Litchfield, Mich., a corporation of Michigan

Filed Feb. 9, 1970, Ser. No. 21,357

Term of patent 14 years

Int. Cl. D21—03

U.S. Cl. D34—5

FIG. 1

FIG. 2

FIG. 3

FIG. 1 is a side elevational view of a playground climber showing my new design, the opposite side being identical thereto;

FIG. 2 is a top plan view, and

FIG. 3 is an end elevational view, the opposite end being identical thereto.

I claim:

The ornamental design for a playground climber, substantially as shown and described.
